UNITED STATES PATENT OFFICE.

ELLISON S. IRELAN, OF ELGIN, ILLINOIS, ASSIGNOR TO ILLINOIS WATCH CASE COMPANY, OF ELGIN, ILLINOIS, A CORPORATION OF ILLINOIS.

DESIGN FOR A WATCHCASE.

Application filed August 22, 1928. Serial No. 27,910. Term of patent 7 years.

To all whom it may concern:

Be it known that I, ELLISON S. IRELAN, a citizen of the United States, residing at Elgin, in the county of Kane and State of Illinois, have invented a new, original, and ornamental Design for Watchcases, of which the following is a specification, reference being had to the accompanying drawing, forming part hereof, in which—

I claim:

The ornamental design for a watchcase, as shown.

ELLISON S. IRELAN.
